GOLF CLUB GRIP FINDER

Frank Strazza, Greenwich, Conn.

Application March 8, 1948, Serial No. 144,962

Term of patent 3½ years

(Cl. D34—5)

To all whom it may concern:

Be it known that I, Frank Strazza, a citizen of the United States, residing at the Round Hill Country Club, Greenwich, Connecticut, in the county of Fairfield and State of Connecticut, have invented a new, original, and ornamental Design for a Golf Club Grip Finder, of which the following is a specification, reference being had to the accompanying drawing, constituting a part thereof.

Fig. 1 is a side elevational view, looking upon the left side thereof.

Fig. 2 is a front elevational view.

Fig. 3 is an elevational view, looking upon the right side.

Fig. 4 is a top plan view looking generally in the direction of the arrows of line 4—4 of Fig. 2.

Fig. 5 is a bottom end view taken on line 5—5 of Fig. 2, and looking in the direction of the arrows thereof.

Fig. 6 is a view to a reduced scale of the golf club grip finder. The dotted lines showing is for illustrative purposes only.

I claim:

The ornamental design for a golf club grip finder, substantially as shown and described.

FRANK STRAZZA.
